NORMAN R. SMITH, OF RED BLUFF, CALIFORNIA.

BALANCED AUTOMATIC AIR-LIFT.

1,112,099.

Specification of Letters Patent. Patented Sept. 29, 1914.

Application filed September 17, 1913. Serial No. 790,339.

To all whom it may concern:

Be it known that I, NORMAN R. SMITH, a citizen of the United States, residing at Red Bluff, in the county of Tehama and State of California, have invented new and useful Improvements in Balanced Automatic Air-Lifts, of which the following is a specification.

This invention relates to a balanced air-lift pump.

It is the object of this invention to provide a pump by means of which a large volume of liquid can be raised with the expenditure of a comparatively small amount of energy, and which is so constructed and operated that the static weight of the column of liquid in a well will assist in elevating a quantity of liquid in the pump cylinder.

A further object is to provide a pump of the above character which is simple in construction and efficient and reliable in operation.

Other objects will appear hereinafter.

The invention primarily resides in a pair of pump cylinders mounted on a walking beam to reciprocate in a well casing, pistons on the lower ends of the pump cylinders, and means for reciprocating the pistons in relation to the pump cylinders by which alternate charges of liquid and air will be forced into the pump cylinders.

The invention further consists of the parts and the construction and combination of parts as hereinafter more fully described and claimed, having reference to the accompanying drawings, in which—

Figure 1 is a front elevation of the invention, with parts broken away. Fig. 2 is a side elevation, with parts broken away. Fig. 3 is a detail vertical section of the lower portion of a pump cylinder, showing the piston and valve construction. Fig. 4 is a detail perspective view of the valve in the piston.

In the drawings A and B represent a pair of well casings, and 2 indicates a timber support for the pump which extends over the upper end of the casings A and B. Mounted on the frame 2 is a rock-shaft 3, carrying a walking-beam 4. Pivoted at 5 to the walking-beam 4, at equal distances on opposite sides of the rock-shaft 3, are tubular pump casings 6 and 6' which extend downward into the liquid contained in the casings A and B and

extend upward a suitable distance above the walking-beam 4, and are formed with a horizontal open-ended portion 7 leading to any suitable point of discharge. The pump casings 6 and 6' are of corresponding weights and dimensions so as to be normally balanced on the walking-beam 4. Mounted on the lower end of each pump cylinder 6 and 6' is a foot-valve which essentially consists of a ball 8 slightly smaller than the inside diameter of the pump cylinders and normally seated on a valve seat 9, to close an inlet opening 10. Surrounding the lower end of each pump cylinder 6 and 6' is a cylindrical hollow piston 11 which is adapted to have slidable movement exterior to the pump cylinders 6 and 6'. Piston rods 12 connect with the pistons 11 and extending upward are secured to sleeves 13, slidable on the pump cylinders. The sleeves 13 are connected to the outer ends of the walking-beam 4, by means of links 14, in such manner that when the lever is rocked the pistons 11 will be reciprocated on the lower ends of the pump cylinders in opposite directions. The lower end of each piston 11 is provided with a cone-valve 15 which extends horizontally through a casing formed in the piston 11. Formed in the valve 15 is a port 16 which is designed to register with ports 17 in the valve-casing to open communication between the interior and the exterior of the piston 11 at its lower end. The valve 15 is adapted to be turned to close the ports 17, and is operated by means of a rocker-arm 18, pivoted at its center on the sleeve 13 and connected at its ends by cables 19, or their equivalents, to the ends of a cross-bar 20, rigidly mounted on the valve 15. The operation of the rocker-arm 18 is effected by means of stop-pins 21 and 22 extending into the path of travel of the rocker-arm 18, and arranged to engage the latter to rock it at the upper and lowermost positions of the sleeve 13. The valve 15 is also formed with a port 23 which is adapted to open communication between the interior of the cylinder 11 and the atmosphere through a pipe 24 when the ports 17 are closed, and to close the communication to the atmosphere when the ports 17 are open; the port 17 being in the form of a channel or depression in the face of the valve 15, which is positioned to register with a port 25 opening to the interior of the piston 11 and with the open terminal of the pipe 24.

In the operation of the invention the rock-shaft 3 is rocked by means of a handle 26, or in any other suitable manner. The rocking of the shaft 3 operates the walking-beam 4 in such manner that the pump-cylinders 6 and 6' will be reciprocated in unison in opposite directions so that when one pump-cylinder is in its uppermost position the other pump-cylinder will be in its lowermost position, as shown in Fig. 1. When the pump-cylinders are thus positioned, the piston 11 on the lowermost pump-cylinder will be in its lowermost position and the valve 15 thereon will be disposed with the port 16 registering with the ports 17, so that the liquid in the well will flow into the space between the valve 8 and the lower end of the piston 11, and thence into the pump-cylinder, through the foot-valve, as will be later described. The piston 11 on the uppermost pump-cylinder will be in its uppermost position and the valve 15 will be disposed with the port 23 registering with the port 25 and the open lower end of the pipe 24; the ports 17 being closed when the valve 15 is thus positioned.

The cycle of operation of one of the pump-cylinders will now be as follows: On the downward movement of the uppermost pump-cylinder, the piston 11 thereon will be caused to move downward away from the lower end of the pump-cylinder, thereby drawing air into the space below the foot-valve 8, through the pipe 24, and ports 23 and 25. When the pump-cylinder nears its lowermost position the rocker-arm 18 will be engaged by the pin 22 and thereby be rocked in such manner as to rock the valve 15 to close the air inlet ports 25 and open the liquid inlet ports 17. The pressure of the column of liquid in the well casing will now operate to force the air trapped in the piston 11 upward, through the foot-valve 8, into the lower end of the pump-cylinder; the ball being lifted by the pressure therebelow. The air will pass around the ball of the foot-valve in a state of compression and will form an air piston in the pump-cylinder above the foot-valve, which air piston will be moved upward in the pump-cylinder by the inflow of liquid which will enter the pump-cylinder until the determined quantity is within the pump-cylinder, whereupon the inflow is cut off at the termination of the upward stroke. The upward movement of the air piston will lift the column of liquid thereabove, and when the pump-cylinder is full, will cause a quantity of liquid equal in volume to that last taken in to be discharged from the open upper end of the pump-cylinder.

When the desired amount of liquid has been forced into the upward moving pump-cylinder through the open port 17, the upward stroke is terminated by means of the

hand-lever 26 and its connections and the closing of the port 15 is effected. The pressure from the liquid in the well is shut off from the pump, thus causing the weight of the liquid in the uppermost pump-cylinder to close the ball valve and prevent back flow into the piston 11 on the down stroke of the latter. The pump-cylinder on now being moved to its upper-most position, the piston 11 will be restored to its uppermost position; the valve 15 being operated by the rocker-arm 18 striking the pin 21 so as to close the port 17 and open the port 25 to the atmosphere when the piston 11 is in its uppermost position. This completes the cycle of operation of one of the pump-cylinders; the other pump-cylinder operating in a like manner.

It will be seen that when the pump is in operation the pump-cylinders will be filled with alternate layers of liquid and air, as shown in Fig. 3; the pump-cylinders being of such diameter and the volume of air delivered thereto of such quantity that the air pistons formed in the pump-cylinders will not be broken by the capillary attraction of the liquid in the pump-cylinders. By thus forming alternate layers or strata of liquid and air in the pump-cylinders the weight of the column of liquid in the well will operate to elevate the upper layers of the liquid in the pump-cylinder to a point above the surface of the liquid in the well, when the pump-cylinder is in its lowermost position, and to a point where equalization of pressure will be established.

By terminating the upper end of the pump-cylinder at a point below the height at which the liquid can be raised in the pump-cylinder by the external pressure of the liquid in the well, a quantity of the liquid in the pump-cylinder will be discharged when the ports 17 are open, which is when the cylinder is in its lowermost position and during its upward movement; the discharge from the pump-cylinder ceasing when the ports 17 are closed or when the pump-cylinder is raised to a point at which the column of liquid and air in the pump-cylinder will exert a pressure equal to or greater than the pressure of the liquid in the well.

The discharge opening of the pump-casing is preferably arranged at a point just below the maximum lift of the liquid column in the well when the pump-cylinder is in its uppermost position so that there will be a discharge from the pump-cylinder on the major portion of its upstroke, thus freeing the pump-cylinder of the weight of the column of liquid therein during its upward movement; the column of liquid in the cylinder being then supported by the pressure of the liquid in the well. By this arrangement the weight of the col-

umn of liquid confined in the downwardly moving pump-cylinder will assist in moving the other pump-cylinder upward on the first half of the stroke.

5 It is important that the foot-valve 8 be formed of a loose ball, as the globular formation facilitates the flow of the alternate charges of liquid and air and insures the formation of the liquid and air in alternate 10 layers.

The quantity of air delivered to the pump-cylinder is regulated by adjusting the length of stroke of the piston 11 which is accomplished by connecting the links 14 at 15 various points on the walking-beam 4 in relation to the pivot 3. For this purpose a series of perforation 4' are formed in the beam 4 which are adapted to receive the pivot pin at the upper ends of the links.

20 The ports 17 are designed to remain open throughout the upward movement of the pump cylinder; the amount of liquid passing therethrough and entering the pump cylinder being controlled by the speed at 25 which the walking-beam is rocked.

Having thus described my invention what I claim and desire to secure by Letters Patent, is:

1. A pump-cylinder comprising a pair of 30 reciprocating pump-cylinders, means for moving said pump-cylinders simultaneously in opposite directions, and means for delivering alternate charges of liquid and air to the pump-cylinders on the reciprocation 35 thereof.

2. In a pump, a pair of reciprocating pump-cylinders, means for moving said pump-cylinders in unison in opposite directions, pistons on the lower ends of said 40 pump-cylinders, means for reciprocating the pistons in advance of the pump-cylinders, and means controlled by the reciprocation of the pump-cylinders and pistons by which alternate charges of liquid and 45 air will be delivered to the pump-cylinders.

3. In a pump, a pair of reciprocating pump-cylinders, means for moving said pump cylinders in unison in opposite directions, pistons on the lower ends of said 50 pump-cylinders, means for reciprocating the pistons in advance of the pump-cylinders, means controlled by the reciprocation of the pump-cylinders and pistons by which alternate charges of liquid and air will be 55 delivered to the pump-cylinders, and means by which the weight of the liquid in the well will operate to force the liquid in the pump-casings to discharge.

4. In a pump, a walking-beam, a pair of 60 balanced pump-cylinders on said walking-beam, a piston on the end of each of the pump-cylinders, connections between the walking-beam and the pistons for reciproc-

cating the latter, means controlled by the piston for trapping air in the pump-cylinders, and a valve in the piston for admitting liquid to the pump-cylinders. 65

5. In a pump, a reciprocating pump-cylinder, a foot-valve thereon, an external piston, means by which said piston will trap 70 air below the foot-valve to form an air piston, and valved means for admitting liquid to the pump-cylinder by which the external pressure of the liquid in which the pump-cylinder is submerged will operate 75 to raise liquid in the pump-cylinder.

6. In a pump, a walking-beam, a pump cylinder on said walking-beam arranged approximately midway between the outer end of the beam and its pivotal mounting, a 80 sleeve slidable on said pump cylinder, a link connecting the sleeve to the walking-beam, a piston on the exterior of the pump casing at its lower end connected to the sleeve, a rock-valve in said piston, a rock-arm on the sleeve connected to the rock-valve, stops for actuating the rocker-arm on the up and down strokes of the pump cylinder to operate the rock-valve and admit alternate charges of liquid and air to 85 the pump-cylinder. 90

7. In a pump, a walking-beam, a pump cylinder on said walking-beam arranged approximately midway between the outer end of the beam and its pivotal mounting, a 95 sleeve slidable on said pump cylinder, a link connecting the sleeve to the walking-beam, a piston on the exterior of the pump casing at its lower end connected to the sleeve, a rock-valve in said piston, a rocker-arm on the sleeve connected to the rock-valve, stops for actuating the rocker-arm on the up and down strokes of the pump cylinder to operate the rock-valve and admit alternate charges of liquid and air to the 100 pump-cylinder, and means for regulating the volume of liquid and air admitted to the pump-cylinder. 105

8. In a pump, a walking-beam, a pair of balanced pump-cylinders on said walking-beam, a piston on the end of each of the pump-cylinders, connections between the walking-beam and the pistons for reciprocating the latter, means controlled by the piston for trapping air in the pump-cylinders, a valve in the piston for admitting liquid to the pump-cylinders, and means for adjusting the length of the piston stroke. 110

In testimony whereof I have hereunto set my hand in the presence of two subscribing witnesses. 115
